(57) **CLAIM**

The ornamental design for an expansion joint installation tool, as shown and described.

DESCRIPTION

FIG. 1 is a perspective view of the expansion joint installation tool showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side view thereof; and,

FIG. 7 is a right-side view thereof.

The expansion joint installation tool is shown with a broken line symbolic break in its length. The appearance of any portion of the article between the break lines forms no part of the claimed design.
